COIN OPERATED DISPENSER

Herbert F. Page, Toledo, Ohio, assignor of fifty per cent to Walter E. White, Toledo, Ohio

Application January 26, 1953, Serial No. 333,165

10 Claims. (Cl. 194—72)

The present invention relates to coin operated dispensers and more particularly relates to what may be termed a "throw-away" dispenser.

A primary object of the present invention is to provide a dispenser of the above described character formed from a single blank of sheet material which may be adapted to vend an infinite variety of articles, which articles may be either rigid or flexible and of a variety of shapes and textures.

Another very important object of the invention is to provide a coin operated vending apparatus having a novel magazine construction for holding and guiding the articles to be vended or dispensed from the machine within the dispensing chamber of the machine.

Yet another object of the invention is to form the article holding magazine of the dispensing apparatus from the same blank of material utilized to form the housing for the apparatus.

A still further object of the invention is to provide a throw-away dispenser that may be efficiently loaded as the dispenser is formed from the blank and which is inexpensive enough to be discarded upon emptying of the article holding magazine.

Another feature, ancillary to the last mentioned object, is to provide such an apparatus which is coin operated and from which the coins may be quickly and easily removed prior to discarding the empty dispenser.

The last object of the invention to be mentioned specifically is the provision of a "throw-away" dispenser that may be easily and quickly wall mounted and removed.

These, together with various ancillary objects and features which will later become apparent as the following description proceeds, are attained by this invention, a preferred embodiment of which is shown, by way of example only, in the accompanying drawings, wherein:

Figure 1 is a front view of the blank forming the dispenser prior to the folding of the blank;

Figure 2 is a perspective view of the blank in its partially folded condition showing the formation of the housing from the blank;

Figure 3 is a front view of the dispenser with the front wall of the same being broken away to show the construction of the article holding magazine and the manner in which the dispenser is operated;

Figure 4 is a cross-sectional view of the dispenser taken substantially along section line 4—4 of Figure 3;

Figure 5 is a top, cross-sectional view of the dispenser taken substantially along section line 5—5 of Figure 4;

Figure 6 is a perspective view of the dispenser mounted on a wall;

Figure 7 is an exploded perspective view showing the mounting of the rear wall of the dispenser on a wall mounting plate;

Figure 8 is a perspective view of an article particularly adapted to be dispensed or vended from the dispenser;

Figure 9 is a perspective view of an article ejecting member that may be used with the dispenser;

2

Figure 10 is an enlarged detail view, in section, disclosing a modified form of opening in the dispenser magazine for dispensing another sized article; and

Figure 11 is a view similar to that of Figure 10 showing yet another modified opening in the magazine for dispensing still other articles therefrom.

Reference will not be had to the accompanying drawings in detail wherein like reference numerals are utilized to designate similar parts throughout the various views.

Referring first to Figure 1, the blank forming the dispensing or vending device of the present invention is designated in its entirety by the numeral 10. Working from the bottom of the figure upwardly, it will be seen that the blank is provided with a plurality of weakening lines or score lines 12 dividing the same into a front end wall 14, front wall 16, rear end wall 18, rear wall 20 and a magazine 22. Further, additional weakening or score lines 24 are formed at the top and bottom edges of the front and rear walls 16 and 20, respectively, to provide top end flaps 26 and 28 and bottom end flaps 30 and 32 which flaps form top and bottom walls for the dispenser, respectively.

As will be noted in Figure 1, the magazine forming strip 22 is of a length equal to the front and rear walls 16 and 20, respectively, but is of substantially greater width than either of these walls. In addition, the body of the magazine forming strip 22 is formed with a plurality of longitudinally extending, transversely spaced score lines 34 with portions of the strip adjacent alternate score lines 34 being slotted as at 36 to form article support and guide means. As will be noted, the slotted portions 36 form longitudinally spaced, transversely extending rows on the magazine forming strip 22.

Each slotted portion 36 consists of a V-shaped slit 38 having its apex on a score line 34 with slits 40 parallel to the score line 34 on both sides thereof joining the legs of the V-shaped slit 38. The last mentioned slits 40 form guide tracks for an article supported within the magazine in a manner presently to be described.

The rear end wall 18 is provided with a plurality of diagonally disposed, longitudinally spaced coin slots 42 aligned with the transverse rows of slotted portions 36 while the front end wall 14 and a portion of the front wall 16 are provided with a plurality of weakened, disk-shaped portions 44 also aligned with the transverse rows of slotted portions 36 in the magazine forming strip 22.

The free longitudinal edges of the front end wall 14 and the magazine forming strip 22 are formed with spaced tabs or lugs 46 and 48, respectively, projecting therefrom while the rear wall 20 adjacent the score line 12 joining this wall to the end wall 18 is provided with a plurality of longitudinally spaced slots 50 and the magazine forming strip 22 adjacent its juncture with the rear wall 20 is formed with a plurality of similar slots 52.

The top and bottom end flaps 26 and 30, respectively, are formed with struck out tabs or lugs 54 while the top and bottom end flaps 28 and 32, respectively, are formed with slots 56.

Referring now to Figure 2, the manner of assembly or folding of the blank 10 to form the complete dispenser or vending device 58 (Figure 6) may be readily observed. As shown in this figure, the front and rear walls 16 and 20 are folded toward one another about their junctures to the rear end wall 18. The magazine forming strip 22 is folded about its juncture to the rear wall 20 to a position overlying the rear wall 20 between the front wall 16 and the rear wall 20. The magazine forming strip 22 is then folded along its score lines 34 back and forth upon itself to form a zig-zag shape with the score lines 34 forming ridges abutting the front and rear walls 16 and 20, respectively. Tabs 48 on the free edge of the strip 22 are then in registry with the slots 50 in the

rear wall 20 and are consequently pressed therethrough to rigidly attach the strip 22 in its folded position. Then, the tabs 46 formed on the free edge of the front end wall 14 are likewise in registry with the slots 52 formed on the magazine forming strip 22 and are pressed therethrough to form a housing of substantially rectangular shape. To complete the housing, the top and bottom flaps 28 and 32 are folded over and the other top and bottom flaps 26 and 30 are also folded over in overlying relation to the flaps 28 and 32, and the tabs 54 are pressed through the slots 56 to complete the housing.

Referring now to Figures 3-5, it will be seen that the slotted portions 36 formed on the ridges created by the folding along the score lines 34 all lie against the inner surface of the front wall 16 of the housing. The V-shaped slits 38 are pressed inwardly at their apices toward the rear wall 20 to form wedge-shaped openings 60. The longitudinal slits 40 on opposite sides of the score lines 34 form guide tracks for an article which is supported within the cut out portions 60.

Noting particularly Figure 8, a disposable toothbrush is shown utilizing the handle portion which is specifically adapted for use in the magazine 22 of the dispenser. As will be noted, the brush is designated in its entirety by the numeral 62 and comprises essentially an elongated, grid strip of material which may be of metal, wood, or any other suitable and well known material. The handle 64 is L-shaped in cross-section and includes a first leg 66 depending from a second horizontal leg 68. At one end of the horizontal leg 68 the brush head 70 is fixed while at the other end of the horizontal leg 68 is an upstanding projection 72, the outer surface of which is serrated as at 74. The lower flange or depending leg 66 of the handle 64 is provided with wedge-shaped cut outs or notches in its lower edge.

Referring now to Figure 3, it will be seen that the horizontal legs 68 of the handles rest upon the lower edge of the triangular cut out 60 while the vertically depending leg or flange 66 rides in the slits 40. The upstanding projection 72 at the rear end of the horizontal flange or leg 68 is disposed adjacent a coin slot 42.

To eject an article 62 from the dispenser, a coin is inserted through a coin slot 42 into abutting engagement with the serrated surface 74 of the upstanding projection 72 and the coin is then pressed into the housing forcing the head portion 70 of the brush through a weakened disk 44 in the front and front end wall of the housing.

In this connection, it is to be noted that the coin slots 42 are slightly widened at their central portions and are a length slightly less than the diameter of a coin to be inserted thereinto. The reason for this is that ordinarily the pressure of the paper, cardboard or other bendable material forming the housing would ordinarily tend to bind the sides of the coin, or rather, the faces of the coin, against the sides of the slot and prevent the coin from dropping after the same has been pressed into the housing. With the present set-up, wherein the central portion of the slot is made wider and the length of the slot slightly less than the diameter of the coin provides an element of certainty that the coin will not drop and must be pressed at least one half of its diameter through a coin slot before the upper and lower edges of the slot will release the coin so that the same may drop to the bottom of the box or housing.

In connection with the movement of the coin into the housing and the corresponding movement of the handle 64 of the brush, after the coin has been pressed into the housing and dropped into the bottom of the box, the notches 74 formed in the lower flange 66 of the handle 64 seat at the bases of the vertical slots 40 to prevent further movement of the brush. This is to prevent accidents by virtue of the entire brush slipping through the front end wall of the housing upon insertion of the coin through the rear end wall of the housing. With this

present arrangement, when the head of the brush projects through the front end wall of the housing, it is merely necessary for the operator to finish pulling the brush out of the dispenser by hand.

With this particular magazine arrangement for supporting the article, such as the brush 62, it will be seen that the present dispenser is enabled to utilize an accordion pleated magazine in such a manner that a very great number of vertically stacked articles may be placed in an exceedingly small area and in a manner which is practical, simple and exceedingly inexpensive of production.

It should be noted in this connection that to further rigidify the magazine strip 22 within the housing, tabs 15 are struck out from the score lines 34 alternating from those score lines 34 from which the slotted portions 36 are formed. These tabs are designated by the numeral 76 and register with corresponding slits 78 in the rear wall 20 of the housing, and are pressed therethrough 20 to prevent buckling of the magazine strip 22 as articles are dispensed therefrom.

To facilitate mounting the dispenser 58 on a wall or the like, the rear wall 20 of the dispenser is formed with a plurality of Z-shaped slits 80 terminating in key-shaped 25 openings 82. A backing plate or mounting plate 84 having a plurality of pegs 86 projecting from the surface thereof is mounted upon a wall and the rear wall 20 of the dispenser 58 is pressed against the pegs 86 so that the pegs enter the keyways 82. Then, the dispenser is 30 moved vertically downwardly, then to the left and then again vertically downwardly to lock the rear wall 20 on the pegs 86 and against the surface of the mounting plate 84.

It is to be noted that the present dispenser can handle 35 both soft articles and so-called hard or rigid articles such as the brush shown in the preferred embodiment. When handling hard articles or soft articles of various contours, the cut out portions in the score lines 34, as illustrated at 36, may be varied to form various 40 shapes as those shown in Figures 10 and 11 and designated by the numerals 86 and 88. Thus, the opening 86 may be utilized for a pack of cigarettes while the opening 88 could be utilized for a tube dispenser such as glue, toothpaste, etc. When such articles are to be 45 dispensed from the machine or apparatus 58, an ejector rod is provided which is substantially of the same shape as that shown in the handle of the brush 62. Thus, the same is shown as being an angle member having a first horizontal flange 90 and a depending flange 92 50 with the horizontal flange 90 having an upwardly extending tab or lug 94 at the rear end thereof for engagement with a coin while the depending flange or lower flange 92 is provided with a pair of cut outs or notches 96 which are adapted to seat in the guide slots 98 and 55 100, respectively, of the various shaped openings 86 and 88, respectively, shown in Figures 10 and 11 upon release of the coin pressure on the article to be dispensed.

As shown in Figure 6, the front wall of the housing 60 may be provided with a plurality of window openings 102 so that the merchandise carried by the magazine may be readily observed.

When the device is empty and the magazine exhausted, a weakened portion is provided at the lower corner of the rear wall 20, illustrated by the numeral 104, from 65 which coins may be extracted from the device. Since this coin pocket will not be exposed until the housing is torn from the pegs 86 on the wall plate 84, little danger of theft is likely. Further, the diagonal disposition of the coin slots 42 correctly guides the coins 70 in their downward movement through the housing and prevents lodging of the coins between the articles to be dispensed.

From the foregoing description, the construction and 75 operation of the devices are believed to be readily apparent and further description is, consequently, believed

to be unnecessary. However, since numerous modifications and changes will readily occur to those skilled in the art after careful perusal of the foregoing specification taken in conjunction with the accompanying drawings, it is not desired to limit the invention to the exact construction shown and described. But, all suitable modifications may be resorted to that fall within the scope of the appended claims.

What is claimed as new is as follows:

1. An article dispenser comprising a housing including front and rear walls and side walls, an article supporting magazine within said housing, said magazine comprising a zig-zag shaped strip of material having spaced ridges abutting said front and rear walls, said strip having a plurality of spaced rows of article guiding and supporting means formed on the ridges abutting said front wall, weakened portions on one of said side walls aligned with said supporting means for dispensing an article from the housing and coin slots on the other of said side walls aligned with said guide means for insertion of a coin for pressing articles through said weakened portions.

2. An article dispenser comprising a housing including front and rear walls and side walls, an article supporting magazine within said housing, said magazine comprising a zig-zag shaped strip of material having spaced ridges abutting said front and rear walls, said strip having a plurality of spaced rows of article guiding and supporting means formed on the ridges abutting said front wall, means attaching the ridges abutting said rear wall thereto, weakened portions on one of said side walls aligned with said supporting means for dispensing an article from the housing and coin slots on the other of said side walls aligned with said guide means for insertion of a coin for pressing articles through said weakened portions.

3. An article dispenser comprising a housing including front and rear walls and side walls, an article supporting magazine within said housing, said magazine comprising a zig-zag shaped strip of material having spaced ridges abutting said front and rear walls, said strip having a plurality of spaced rows of article guiding and supporting means formed on the ridges abutting said front wall, weakened portions on one of said side walls aligned with said supporting means for dispensing an article from the housing and coin slots on the other of said side walls aligned with said guide means for insertion of a coin for pressing articles through said weakened portions, said rear wall being slotted to facilitate mounting of the dispenser on a support.

4. An article dispenser comprising a housing including front and rear walls and side walls, an article supporting magazine within said housing, said magazine comprising a zig-zag shaped strip of material having spaced ridges abutting said front and rear walls, said strip having a plurality of spaced rows of article guiding and supporting means formed on the ridges abutting said front wall, weakened portions on one of said side walls aligned with said supporting means for dispensing an article from the housing and coin slots on the other of said side walls aligned with said guide means for insertion of a coin for pressing articles through said weakened portions, a backing plate for said dispenser having projecting lugs thereon, said rear wall having locking slits engaging said plate to mount the housing thereon.

5. An article dispenser comprising a housing including front and rear walls and side walls, an article supporting magazine within said housing, said magazine comprising a zig-zag shaped strip of material having spaced ridges abutting said front and rear walls, said strip having a plurality of spaced rows of article guiding and supporting means formed on the ridges abutting said front wall, weakened portions on one of said side walls aligned with said supporting means for dispensing an article from the housing and coin slots on the other of said side walls aligned with said guide means for insertion of a coin for pressing articles through said weakened por-

tions, said housing being rectangular and further including top and bottom walls, the ridges of said strip extending vertically between said top and bottom walls.

5 6. A throw-away dispenser formed from a substantially rectangular blank of sheet material, said blank having score lines thereon dividing the same into a front end wall, a front wall, a rear wall, a rear end wall and a magazine forming strip, flaps formed at the top and bottom edges of said front and rear walls constituting top and bottom walls respectively, said magazine forming strip having a plurality of transversely spaced, longitudinally extending score lines thereon and being of substantially greater width than said front and rear walls, portions of said magazine strip adjacent alternate score lines being slotted to form article supports, said slotted portions forming longitudinally spaced, transversely extending rows, said rear end wall having diagonally disposed, longitudinally spaced coin slots therein aligned with said transverse rows and said front end wall having weakened portions thereon aligned with said transverse rows.

25 7. A throw-away dispenser formed from a substantially rectangular blank of sheet material, said blank having score lines thereon dividing the same into a front end wall, a front wall, a rear end wall, a rear wall and a magazine forming strip, flaps formed at the top and bottom edges of said front and rear walls constituting top and bottom walls respectively, said magazine forming strip having a plurality of transversely spaced, longitudinally extending score lines thereon and being of substantially greater width than said front and rear walls, said magazine strip being folded along said score lines to a zig-zag shape with adjacent score lines abutting the inner surfaces of said front and rear walls respectively, 30 portions of said magazine strip adjacent alternate score lines being slotted to form article supports and guide means, said slotted portions forming longitudinally spaced, transversely extending rows, said front and rear end walls having weakened portions and coin slots therein respectively aligned with said transversely extending rows whereby insertion of a coin through one of said slots presses an article through one of said weakened portions.

35 8. The combination of claim 7 wherein said slotted portions each consist of a V-shaped slit having its apex on a score line and slits parallel to said score line on both sides thereof joining the legs of said V-shaped slit to form guide tracks.

40 9. A disposable article dispenser comprising a housing including front, rear and end walls, an article supporting magazine within said housing for supporting articles in superposed relation within said housing, one of said end walls having weakened portions thereon in alignment with said supporting means for dispensing articles from the housing, the other of said end walls having coin slots therein aligned with said supporting means for the insertion of coins to press articles through said weakened portions.

45 10. An article dispenser comprising a housing including front, rear and end walls, an article holding magazine within said housing, said magazine including article supporting means for slidably supporting articles in superposed relation within said housing, one of said end walls having article ejection perforations therein aligned with said article supporting means, the other of said end walls having coin openings therein aligned with said article supporting means for the insertion of coins to press articles through the ejection perforations.
